UNITED STATES PATENT OFFICE.

MINFORD S. CLARK, OF NEW YORK, N. Y., ASSIGNOR TO CHARLES HARRISON, OF SAME PLACE.

IMPROVEMENT IN REVERSIBLE FAUCET-FILTERS.

Specification forming part of Letters Patent No. 177,094, dated May 9, 1876; application filed December 2, 1875.

To all whom it may concern:

Be it known that I, MINFORD S. CLARK, of New York, N. Y., have invented an Improvement in Reversible Faucet-Filters, of which the following is a specification:

My improvement relates to that class of faucet-filters in which an annular filtering-body is established in the central portion of an annular chamber surrounding the conical bearing of a hollow faucet-plug, provided with an internal diaphragm; and my invention consists in extending the internal diaphragm downward from the upper end of the faucet-plug to a point opposite the lower boundary of the external filter-chamber, then extending it laterally to one side of the plug, and in providing a series of lateral openings in the plug, and corresponding openings in the bearing-wall of the plug, which is also the internal wall of the annular filter-chamber, whereby the chamber formed inside the hollow plug constitutes the passage for conveying fluid from the supply-pipe directly into the lower part of the filter-chamber beneath the filtering-body therein contained.

In my invention this internal chamber of the faucet performs the double function of admitting water directly into the upper part of the filtering-chamber, or directly into the lower part of the filtering-chamber, at the pleasure of the operator, and thereby dispenses with the necessity of establishing any vertical passage outside the plug-bearing for supplying water to the lower part of the filter-chamber.

The accompanying drawings are as follows:

Figure 1 is a vertical section through the center of my faucet-plug and filtering-chamber. Fig. 2 is a transverse section through the line *x-x* on Fig. 1. Fig. 3 is a transverse section through the line *y-y* on Fig. 1.

Referring to the drawings, *A* represents a hollow conical faucet-plug. A portion of the interior of the hollow plug is partitioned off by the diaphragm *a*, for the purpose of establishing the induction-chamber *d*, while the remainder of the hollow space within the plug constitutes the outlet-passage *c*. The faucet-plug is seated in the conical bearing *d*, which

constitutes the inner wall of the annular filtering-chamber *e*.

The lower part of the filtering-chamber is provided externally with a male screw-thread, which engages a corresponding female thread upon the inside of the cap *e²*. This cap has an annularly-recessed shoulder for engaging the annular packing-ring *e³*, and the wall *d* of the conical plug-chamber is provided with the external collar *d¹*, for engaging another packing-ring, *d²*, interposed between the collar *d¹* and the inside of the cap *e²*. The packing *e³* makes a tight joint between the shell of the filtering-chamber and the cap, and the packing *d²* makes a tight joint between the collar *d¹* on the exterior of the conical plug-seat and the inside of the cap, which is perforated at the point to receive the end of the conical seat *d*.

The filtering material *f* is contained in the annular box *f¹*, the upper and lower sides of which are perforated, as shown at *f²*. The interior of the filtering-chamber *e* is counter-bored to receive the filter-box *f¹*, which is held in position by the inner edge of the cap-shoulder. The upper part of the induction-chamber *b* has two lateral perforations, *b¹* and *b²*. The lower end of the induction-chamber has another perforation, *b³*, which is immediately under the perforation *b¹*. In the position in which the parts are shown in the drawing, the perforation *b¹* is immediately opposite the supply-pipe *g*, while the perforation *b³* is immediately opposite a corresponding aperture, *g¹*, in the wall of the plug-seat, so that water discharged into the induction-chamber from the supply-pipe *g* is discharged through the apertures *b³* and *g¹* into the lower part of the filtering-chamber. By giving the plug a quarter-turn the perforation *b²* will be brought opposite the supply-pipe *g*, and in that case the perforation *b¹* will coincide with the perforation *g²* in the wall *d*. In this case the fluid supplied through the pipe *g* will be discharged from the induction-chamber *b*, through the apertures *b¹* and *g²*, into the upper part of the filtering-chamber.

In the position shown in the drawing, fluid discharged into the lower part of the filtering-

chamber passes upward through the filter *f* into the upper part of the filtering-chamber, and from thence, through the aperture *h* in the wall *d* and the aperture *c*¹ in the conical plug, into the outlet-passage *c* of the plug.

In the other position described, fluid discharged into the upper part of the filtering-chamber passes downward through the filter into the lower part of the filtering-chamber, and from thence, through the perforation *h'* in the wall *d* and the perforation *c*² in the plug, into the outlet-passage *c*, from whence it is discharged, as before.

By the described organization of the parts of my faucet-filter I am able to construct with special economy a faucet-filter in which fluid may be discharged through the filtering material in either an upward or a downward direction, at pleasure.

I claim as my invention—

1. In a reversible faucet-filter, the hollow faucet-plug A, provided with the interior dia-

phragm *a*, extending downward from the upper portion of the plug to a point opposite the lower boundary of the external filter-chamber, and then extending laterally to one side of the plug, the exterior shell of the plug being provided with the perforations *b*¹, *b*², *b*³, *c*¹, and *c*², substantially as and for the purposes set forth.

2. A hollow faucet-plug provided with the interior diaphragm, extending downward from the upper portion of the plug to a point opposite the lower boundary of the external filter-chamber, and then extending laterally to one side of the plug, and provided with the perforations *b*¹, *b*², *b*³, *c*¹, and *c*², in combination with the supply-pipe *g* and the annular filtering-chamber *e*, the interior wall of which is provided with the perforations *g*¹, *g*², *h*, and *h'*, substantially as and for the purposes set forth.

MINFORD S. CLARK.
